Attorney.

UNITED STATES PATENT OFFICE

WALTHER GOSMANN, OF DORTMUND, GERMANY

HAND FIRE EXTINGUISHER

Application filed December 16, 1927, Serial No. 240,526, and in Germany October 1, 1927.

The present invention relates to a hand fire extinguisher of the type having a container for an extinguishing fluid under pressure and specifically relates to an improvement 5 therein involving the provision of a frangible nozzle whereby the extinguishing fluid is released when the glass nozzle communicating with the delivery pipe is demolished. It is a further object of the invention to 10 provide a specific mounting for the frangible nozzle so that after use it can be readily replaced for re-use.

In addition, the cover of the tank containing the extinguishing agent is provided 15 with a filling stopper in which is fitted a ball valve serving as a check valve when putting the tank under pressure. After this has been effected, the threaded branch 20 of the valve casing for connecting thereto the air pump is closed by a screw cap so as to provide against any possible leakage of air past the check valve.

The apparatus provided by this invention is shown in the accompanying drawing by 25 way of example.

Fig. 1 is a vertical section, and

Fig. 2 is a plan view of the discharge nozzle on an enlarged scale.

The tank *a* is filled with the extinguishing 30 agent *b* through the aperture provided in the filling stopper *c*, the height to which it can be filled being limited by the tube *d* which is firmly secured to the check valve casing *e*. The filling stopper *c* is then screwed down 35 air-tight, and the glass tube *f* fitted air-tight into the branch of the nozzle *j* by means of a metal tube *g* into which said glass tube is tightly fitted. The nozzle *j* is, in turn, screwed into the cover *k*. The metal tube 40 *g* is provided with two windows or sight openings *h*—*h* disposed opposite one another through which the fire-extinguishing fluid may be observed as long as a normal or 45 standard pressure exists in the tanks. The glass tube communicates with the delivery pipe *m* which reaches to the bottom of the tank. By observing the tube *f* through the windows or sight openings *h*, it is easy to ascertain whether or not the extinguisher is 50 in condition for use, or, in other words,

whether or not there is sufficient pressure in the tank to effect spraying of the fluid.

What I claim as new and patentable is:—

1. A hand fire extinguisher comprising a container for an extinguishing fluid under 55 pressure, and a closure for the container, a tube within the container for the delivery of the fluid, a nozzle upon the closure supporting the tube at its delivery end and including a frangible, and transparent closed tube 60 upon the nozzle in communication with the said nozzle and tube, and a metal tube enclosing a portion of the frangible tube and having a sight opening therein whereby the presence of the extinguishing fluid, under 65 pressure, may be observed, said frangible and transparent closed tube being replaceable after use of the extinguisher for reuse thereof.

2. A hand fire extinguisher comprising a 70 container for an extinguishing fluid under pressure, and a closure for the container, a tube within the container for the delivery of the fluid, a nozzle upon the closure supporting the tube at its delivery end, a frangible, 75 and transparent closed tube upon the nozzle in communication with the said nozzle and tube, a filling tube mounted at its upper end in the said closure and depending therein a distance to determine the height to which 80 the container may be filled with the extinguishing fluid, a valve casing to which the said end of the tube is connected, a check valve in said casing, and a closure cap removably fitted onto said casing, whereby, 85 upon its removal, the extinguishing fluid may be supplied to the container, said frangible and transparent closed tube being replaceable after use of the extinguisher for reuse thereof.

In testimony whereof I affix my signature.
WALTHER GOSMANN.
